CENTRIFUGE DRUM

Evert van der Molen, Groningen, Netherlands, assignor to Krauss-Maffei A. G., Munich-Allach, Germany

Application December 11, 1953, Serial No. 397,681

Claims priority, application Netherlands December 13, 1952

10 Claims. (Cl. 210—380)

The invention relates to a centrifuge drum for separating solid constituents from liquid material to be centrifuged, in continuous operation, the side wall of the drum having passage apertures disposed in the longitudinal direction.

In the centrifuging of liquid or pulpy materials preferably in conical centrifuge drums of this type, the viscosity and hence also the friction between the material and the walls of the drum continuously increases during its flow through the drum, in consequence of the gradual extraction of the liquid. The passage of the material to be centrifuged through the drum is thereby rendered difficult, so that it stays therein longer than is required. In order to obviate this difficulty it has already been proposed to increase gradually the angle of inclination of the drum walls to the axis of the drum in accordance with the increase in viscosity and friction from the inlet end towards to the outlet end, and for this purpose to give the centrifuge drum an inwardly bowed sided basket shape. In the known centrifugal drum furnished with circular apertures for the liquid, this shape results in unimpeded and therefore favourable flow of the liquid through the drum only when the inclination of the drum walls corresponds to the particular nature of the material to be centrifuged. In addition, in the known centrifuge drum having circular apertures, the effective screening surface is decreased with the continuously increasing inclination of the drum wall, since only the area of the apertures projected at right-angles to the drum axis is available for the passage of the liquid.

In contradistinction thereto, the object of the invention is to provide a centrifuge drum which ensures for materials of any kind to be centrifuged an unimpeded passage and a uniformly effective removal of water over the entire length of the drum.

According to the invention a centrifuge drum comprises elongate members disposed in relation to each other to form the side wall of a drum having an increasing area from one end to the other said members having passage apertures between them, and drum end elements attached to the ends of said members, said elements being rotatable in relation to one another. The walls may be bowed inwards and the said elements are in planes parallel to each other.

These measures provide a considerably advantageous effect in that the cross-section of the passage apertures available for the radial passage of the liquid is not reduced through the passage apertures, which preferably extend over the entire length of the drum, even in the highly inclined part of the latter, so that removal of water from the material centrifuged is uniform over the entire water extraction path. Through the turning of the ends of the drum which hold the plates, bars, or the like, moreover, extensive adaptation of the inclination of the drum walls to the particular nature of the material centrifuged can be achieved, with the further advantageous result that the plates, bars, or the like are brought into the helical direction of passage of the material centrifuged which

2

reduces wear on the same. These measures therefore ensure a good degree of water removal from the material centrifuged, high efficiency of the centrifuge, and a long life of the centrifuge drum.

5 Exemplified embodiments of the invention are illustrated diagrammatically in the drawing, in which:

Figure 1 is a sectional view of a centrifuge drum, made in accordance with the invention and in which the plates forming the walls of the drum intersect the axis of the

10 drum;

Figure 2 is a perspective view of the centrifuge drum with the end elements relatively rotated so that the plates take up a helical position;

Figure 3 is a perspective view of a plate, the surface of which will form the inner wall surface of the centrifuge drum and consists of a polygonal course of plane surfaces; and

Figure 4 is a sectional view of a complete separator with a centrifuge drum according to the invention.

The material to be centrifuged is introduced into a centrifuge drum 2, disposed vertically or horizontally in a centrifuge and widening in inwardly bowed sided form (like a bow sided basket) towards the outlet end 1, through an inlet pipe (not shown in the drawing) in front 20 of the drum end constructed as a disc 3. During the rotation of the drum, the material to be centrifuged slides under the action of centrifugal force over the drum wall 4, which is inclined in relation to the axis of the drum, to the discharge end 1 of the centrifuge drum 2, from 25 which the material, deprived of water on its sliding path, is thrown out and collected separately from the liquid thrown off. Through the bow-sided form of the centrifuge drum 2, an unimpeded flow of the material to be centrifuged through the centrifuge drum 2 is obtained, 30 because the braking action of the friction of the material being centrifuged on the drum wall, which is increasing because of the increase in viscosity on the water extraction path, is counterbalanced by the inclination of the drum wall 4 which increases towards the outlet end of 35 the centrifuge drum 2. The drum wall 4 consists of elongate members such as plates 5, bars or the like, which are disposed side by side in the longitudinal direction of the centrifuge drum 2 with spacing adjusted to the grain size of the material to be centrifuged. The effect area 40 of the apertures 6, which extend over the entire length of the drum, is not reduced by the inclination of the drum wall 4, which increases in the direction of the outlet end of the centrifuge drum 2. The ends of the plates 5, bars, or the like are secured to drum end elements or rings, for 45 example to a ring 7 provided at the outlet end of the centrifuge drum 2 and at the opposite end of the drum to the disc 3 serving as end wall of the drum. Through a device not illustrated in the drawing, the rings provided at the ends of the drum walls, or the ring 7 and the disc 50 3 can be rotated in relation to one another, and the inclination of the inner wall surface of the centrifuge drum 2 relative to the drum axis can thereby be varied. By this means an adaptation of the inclination of the wall 55 surface to the particular nature of the material introduced, in respect of its viscosity, is permitted. Since the turning of the rings or of the ring 7 and the disc 3 is so effected that the plates 5, bars or the like, are brought into the helical passage direction of the material centrifuged through the centrifuge drum 2, a reduction of the 60 rubbing or wear on the edges of the plates or bars through the material centrifuged is achieved in advantageous manner. The plates 5, bars, or the like are preferably constructed with a rectangular cross-section, and are so disposed in the centrifuge drum 2, that the major axis of 65 this cross-section is directed radially to the axis of the drum. The cross-section of the plates 5, bars, or the like need not however be the same over the entire length of

70

the drum. In addition, their surface forming the inner drum wall 4 may be curved, as shown in Figures 1 and 2, or polygonal as shown in Figure 3, or may also be flat over their entire length. In addition, the plates, bars, or the like may be disposed, in the axial direction of the centrifuge drum 2 (Figure 1), or at an angle thereto (Figure 2) by relative rotation of the drum end elements. The fastening of the plates 5, bars or the like to the rings or to the ring 7 and disc 3 need not be rigid, as shown by way of example in Figures 1 and 2, in which case on the turning of the end elements (rings or ring 7 and disc 3) they bend elastically in the desired direction, but they may be fastened in any other way, for example pivotally. Apart from the end elements, one or more other rings, distributed over the length of the drum, connecting the plates 5, bars, or the like, and disposed parallel to the ends of the drum, may also be provided in order to stiffen the drum walls.

The arrangement of a drum according to the invention in a complete centrifuge is illustrated in Fig. 4.

The side wall of a vertically mounted sieve drum 2 is formed by relatively thin sheet metal bars 5, which terminate at both ends in dovetail guides 34. At the one end of the bars, said dovetail guides fit into the upturned edge 3a of a base disc 3, at the other end in corresponding grooves 35 provided in the edge 7a of a jacket drum 7b enclosing the sieve drum 2. Between the dovetail guides 34 of the sieve bars 5 there are inserted in the groove 35 shim plates (not shown in the drawing) in order to ensure the requisite spacing between the sieve bars 5 for the passage of the centrifuged liquid material. In the base of the jacket drum 7b there are provided discharge apertures 7c for the centrifuged liquid.

The material to be centrifuged is admitted to the centrifuging chamber of the sieve drum 2 through the inflow pipe 32 and flows under the action of centrifugal force upwardly over the inner surface of the sieve drum 2, giving off its liquid content, and is discharged over the edge of the sieve drum 2. The discharged material is received in the collecting chamber 33 of the centrifuge housing 10 surrounding the drums 2 and 7b, and exhausted therefrom through the discharge chute 11. Similarly, the liquid leaving the jacket drum 7b through the discharge apertures 7c is received in a collecting space 13 separated from the collecting space 33 by the partition 12, and is removed therefrom through the discharge chute 14. For driving the drums 2 and 7b there is provided an electric motor 15 which transmits its rotational movement by means of a belt drive 16 to the shaft 17, which is connected with the jacket drum 7b through screws 18. The shaft 17 is hollow, in order to receive an inner shaft 19 to the upper end of which the base 3 of the sieve drum is secured. The non-rotatability of the sieve drum 2 on the shaft 19 is secured by the square head 20 of this shaft and its firm seating on the shaft is secured by the nut 21 and washer 22. A cap 23 covering these securing elements serves at the same time as a material distributor.

In accordance with the invention, the edge 3a of the base 3 can be rotated in relation to the annular edge 7a of the jacket drum 7b. By this means, the inclination of the side surface of the sieve drum 2 is varied, so that it may be adapted to the nature of the centrifuged material as regards the viscosity thereof. For this purpose diametrically opposed curved slots 24 are symmetrically provided in the hollow shaft 17, in which slots engages a pin 26 passing through the inner shaft 19. The ends of this pin rest in a ring 26 which is rotatably mounted, by means of the ball bearing 29, in a ring housing 28 connected with a nut 27. On the ring housing 28 there is arranged a hand wheel 30, by means of which, on rotation of the nut 27, the inner shaft 19 is rotated and at the same time lifted in relation to the hollow shaft 17. Thus the base of the sieve drum 2 is rotated and at the same time lifted in relation to the edge 7a of the jacket drum

7b. The lifting of the inner shaft 19 is necessary because when the sieve bars 5 are placed obliquely, the distance of the base from the edge 7a of the jacket drum shortens.

I claim:

1. A rotary drum for centrifugal separators comprising elongate members disposed in relation to each other to form the side wall of a drum having an increasing area from one end to the other, said elongate members being spaced apart to provide apertures therebetween extending in the direction of said members, a pair of drum end elements to which the ends of said elongate members are connected, and means to turn said drum end elements relatively to one another, thereby to twist said elongate members about the drum axis and so vary the gradient of said side wall.
2. A rotary drum for centrifugal separators comprising elongate members disposed in relation to each other to form the tubular side wall of a drum having an increasing area from one end to the other, said elongate members being spaced apart to provide apertures therebetween extending in the direction of said members, a pair of drum end elements disposed in parallel planes for rotation about a common axis, said end elements having a circular periphery to which the ends of said elongate members are connected, and means to turn said drum end elements relatively to one another about said axis thereby to twist said elongate members and so vary the gradient of said side wall.
3. A rotary drum for centrifugal separators as claimed in claim 1, wherein the elongate members are inwardly bowed over their entire length.
4. A rotary drum for centrifugal separators as claimed in claim 1, wherein the elongate members are each formed of a succession of relatively inclined rectilinear portions.
5. A rotary drum for centrifugal separators as claimed in claim 2, wherein the drum and elements consist of rings.
6. A rotary drum for centrifugal separators as claimed in claim 2, wherein the drum and element at the larger end consists of a ring and the drum end element at the smaller end consists of a disc.
7. A rotary drum for centrifugal separators as claimed in claim 1, wherein the elongate members are of rectangular cross-section, the major axis being disposed radially of the drum.
8. A rotary drum for centrifugal separators as claimed in claim 1, wherein the elongate members are rigidly connected to the drum end elements.
9. A rotary drum for centrifugal separators as claimed in claim 1, wherein the elongate members are pivotally connected to the drum end elements.
10. A rotary drum for centrifugal separators comprising a base end member, a top end member of larger circumference than said base end member, said members being rotatable with respect to each other, and spaced elongate members connecting said base and top end member, said elongate members forming a slotted side wall tapering from said top end to said base end, said taper of the side wall being adjustable by turning one of said end members with respect to the other.
